Primary Examiner—Bernard Ansher**Assistant Examiner—Philip Hyder****Attorney, Agent, or Firm—Michael W. York****[57] CLAIM**

The ornamental design for an outer thigh and gluteal muscle exerciser, as shown and described.

DESCRIPTION

FIG. 1 is a top, front, left end perspective view of an outer thigh and gluteal muscle exerciser showing my new design, the broken line showing is for illustrative purposes only and forms no part of the claimed design; FIG. 2 is a top, front, right end perspective view thereof, the broken line showing is for illustrative purposes only and forms no part of the claimed design; FIG. 3 is a top plan view thereof, the broken line showing is for illustrative purposes only and forms no part of the claimed design;

FIG. 4 is a bottom plan view thereof;

FIG. 5 is a front elevational view thereof, the broken line showing is for illustrative purposes only and forms no part of the claimed design, the rear elevational view being a mirror image thereof; and,

FIG. 6 is a side elevational view thereof, the elevational view of the opposite side being a mirror image of the side shown.

FIG. 4

FIG. 5

FIG. 6
